(57) **CLAIM**

The ornamental design for a grinder with an attached container, as shown and described.

DESCRIPTION

FIG. 1 shows a perspective view of a grinder with an attached container showing my new design.

FIG. 2 shows a rear end elevation view of the grinder with an attached container.

FIG. 3 shows a front end elevation view of the grinder with an attached container.

FIG. 4 shows a right side elevation view of the grinder with an attached container.

FIG. 5 shows a left side elevation view of the grinder with an attached container.

FIG. 6 shows a top plan view of the grinder with an attached container.

FIG. 7 shows a bottom plan view of the grinder with an attached container.

FIG. 8 shows a left side elevation exploded view of the grinder with an attached container; and,

FIG. 9 shows an alternate perspective view of the grinder with an attached container.

The broken lines shown in the drawings form no part of the claimed design.
